COMPARTMENTED CONTAINER FOR COSMETICS OR THE LIKE

Dorothy E. Mathison, Rte. 1, Box 385, Hood River, Oreg.

Filed July 6, 1960, Ser. No. 61,253

Term of patent 7 years

(Cl. D58—13)

Fig. 2

Figure 1 is a perspective view of a compartmented container for cosmetics or the like, embodying my new design;

I claim:

The ornamental design for a compartmented container for cosmetics or the like, as shown.
